MILK BOTTLE INDICATOR

Joseph L. Churchill, Seattle, Wash.

Application July 14, 1947, Serial No. 760,874

5 Claims. (Cl. 116—134)

1

My invention comprises a device which a housewife may apply to a standard milk bottle, such as she returns empty to the dairy, for the purpose of indicating to the deliveryman what products, and how many of each, she desires left. Thus she need not write a note, or risk the subsequent loss of such a note, but can conveniently indicate what she desires. From the deliveryman's standpoint, he could determine, from a distance, what is wanted, and bring it to the door, rather than return to his truck for it after reading a note. From the standpoint of the dairy, increased volume of sales will follow from the convenience with which special delicacies can be ordered.

Devices to the ends indicated have been proposed heretofore, but these have been, so far as I am aware, of such character as to make it necessary either to apply them to the milk bottle while holding in indicating position those indicators which it is desired to employ, which is awkward, or to move the indicating devices, after application to the bottle, into indicating position, and to secure them individually in such indicating position, which also is tedious and difficult.

It is one of the objects of the present invention to provide a device of the general nature indicated, which can be merely dropped in place, or very simply applied to the bottle, and which after application to the bottle will permit the several individual indicators to be moved by a finger to indicating position, and will automatically retain them in such indicating position, without the necessity of further action on the part of the housewife.

It is a further object to provide a device of the general character indicated, which shall be simple and sufficiently cheap to permit it to be given away by the dairy to each customer as a premium or convenience, and which will yet pay for itself many times over by the convenience with which the housewife may indicate her desire for additional or special products, which otherwise she might not bother to order.

It is a further object to provide a device of this sort, which may be stored flat in a drawer, or in similar fashion, and which will occupy little space.

Another object is the provision of such a device which is sufficiently rugged that it will last for an indefinite period.

With such objects in mind, and others as will appear hereinafter, the invention comprises the novel device for use in the manner indicated, such as is shown in a typical form in the accompanying drawings, and such as will be herein-after more fully described and defined.

2

Figure 1 is an elevation of the device applied to a standard milk bottle, illustrating the initial nonindicating position automatically assumed by all the tags, and the manner of moving a tag into indicating position, and Figure 2 is a similar view showing certain tags in such indicating position, and others in nonindicating position, as they would appear to the deliveryman.

Figure 3 is an isometric view, illustrating the device detached from a milk bottle.

The form of the standard milk bottle 9 is well known and widely used. It has a bulbous mouth 91, a somewhat reduced neck 92, sloping shoulders 93, and a main body portion, 94, which is larger than any other part of the bottle, and which in particular is appreciably larger than the bulbous mouth 91. It is with this type of milk bottle that the present device is intended to cooperate.

A plurality of tags, generally designated by the numeral 1, but designated 1a, 1b, 1c, 1d, etc., to distinguish them, differ from one another only in the nature of the indicia which they bear. The tag 1a, for instance, calls for an extra quart of milk, the tag 1c for a pint of cream, etc. Preferably they are printed on both sides, and may be otherwise distinguishable at a distance as by a characteristic color on one or both sides. These tags are of light material, and may be made of sheet metal, or, as is preferred, they may be molded from plastic material. Each one is provided with a pivot means 10, disposed transversely of the tag and located nearer one end than another, but still appreciably spaced from the short end.

These tags are threaded or pivoted on a ring 2, which may be a rigid ring of wire or similar material, or which might be made of more flexible material. Preferably it has some little weight, as related to the combined mass of the tags. Only a few tags have been illustrated, but in practice a large number would ordinarily be employed.

The size of the ring 2 is of importance. It should be of large enough size that it will slip freely over the bulbous mouth 91 of the standard milk bottle 9, yet small enough that it will not slip down over the sloping shoulders 93, but will lodge on the latter, and be thereby supported.

Figure 3 shows the ring 2 and its various tags 1 as the same would appear with the ring supported in a horizontal plane, detached from the bottle. All the tags, by reason of the fact that they are more greatly weighted by their longer end than by their shorter end, will hang more or less vertically downwardly, and will swing freely upon the ring. In this condition the ring is slipped over the mouth of a bottle and comes to rest

with the longer end of all tags hanging downwardly from the ring, as shown in full lines in Figure 1. Now the housewife selects that tag, such as the tag 1b, which indicates the product she wants, and inserting her finger beneath the lower end of this tag, she merely lifts it up and flips it over. In so doing the ring 2 first rises, in the manner shown in dot-dash lines in Figure 1, and then settles back to its initial position, leaving the tag inverted, as are the tags 1a and 1b in Figure 2, so that each tilts upwardly, its longer end projecting above the ring and its shorter end extending below the ring. Once the tag has been tilted upwardly it is only necessary to permit it to slide downwardly along the sloping shoulders 93 of the bottle, and the weight and inward force of the ring holds the uptilted tag flatwise against the bottle, thereby securing it in its uptilted indicating position. The engagement of the short end of the tag below the ring, and of its long end above the ring, with the ring engaged with the now outer face of the tag intermediate the two ends, serves to flatten the tag and hold it against the bottle, and nothing more is needed.

The deliveryman, upon arriving, notes which tags are upturned, and from the written indicia thereon or by the characteristic color of each is informed what products are wanted. He brings these products to the door, removes the ring, leaves it with the delivered products, and carries away the empty bottle which served as the support for the indicating device.

While it has been indicated that the tags are pivoted nearer one end than the other, this is merely a simple manner of effecting the weighting of one end so that it will naturally and normally hang downwardly. However, the same result might be achieved by the use of a greater mass at one end than at the other end, without actual difference in length as between the two ends. It must be remembered, though, that the tag should be reasonably short at one end, at least, in order that it may be tilted over, in the manner shown in dot-dash lines in Figure 1, without unduly raising the tags and ring from the shoulders of the bottle. One of the advantages of the present device is that it may be slipped in place with no tags whatever in indicating position, and thereafter such tags as indicate wanted products may be moved into indicating position simply, and immediately left, without any special precautions being taken to secure them in their indicating position, so long as the device as a whole remains in place upon the milk bottle.

When the device is not in use all the tags can lie more or less in the plane of the ring, and the entire device may be laid in a drawer or hung on a hanger, where it will not occupy any particular amount of room, nor be conspicuous or in the way. It is complete and unitary, and if the ends of the ring are permanently secured there is no likelihood that any tag will be detached or lost. It serves as a constant reminder to the housewife of all the dairy's products, and as a convenience whenever she desires to order some special product, or to vary her normal order.

I claim as my invention:

1. For use upon a standard milk bottle, means to indicate wanted dairy products, comprising a ring of a size large enough to slip over the top of the bottle but too small to slip down over its sloping shoulders, a plurality of tags independently pivoted upon said ring, and each having its

mass located principally below the ring to hang normally pendant therefrom, but including a portion extending above the ring, the ring tilting upwardly as a tag is tilted from its normal pendant position to a reversed, uptilted position, and settling back to hold such uptilted tag in the latter position by pressure of the ring's weight against the bottle, each tag bearing indicia identifying wanted products.

10 2. For use upon a standard milk bottle, means to indicate wanted dairy products comprising a ring of a size large enough to slip over the top of the bottle but too small to slip down over its sloping shoulders, a plurality of flat, elongated

15 tags each bearing indicia indicating wanted products, transversely disposed pivot means on each tag lying in the general plane of the tag, nearer one end than the other, but still spaced from the short end to leave such short end projecting, said tags having their pivot means threaded upon and rotatable about the ring, to hang normally pendant therefrom, but retainable in uptilted position by the inward pressure of the ring intermediate its ends, which are thereby urged against the bottle.

20 3. For use upon a standard milk bottle, means to indicate wanted products comprising a support of a size to extend about the neck of a bottle, but too small to slip down over its sloping shoulders, yet readily yieldable away from the bottle, a plurality of tags mounted upon and for individual pivotal movement each relative to the support, and each weighted to hang normally

25 pendant from the support, and each shaped, in its plane of swing, to engage the bottle at points spaced above and below its pivot axis, whether in normal pendant position or in uptilted position, thereby to be self-retaining in either such position by inward pressure of the support, each 30 such tag bearing indicia identifying an individual wanted product.

35 4. For use upon a standard milk bottle, a support formed to extend more than half-way around the neck of such a bottle, to be thereby supported upon, but for movement relative to such bottle, a plurality of individual indicators supported upon and separately movable relative to said support, from nonindicating to indicating position, each of said indicators having a generally 40 flattened face engageable with the bottle and held thereagainst by the bottle-supported support, for retention in an indicating position, but being biased to remain, unless moved into such engagement, in nonindicating position.

45 5. For use upon a standard milk bottle, a support formed to extend more than half-way around the neck of such a bottle, to be thereby supported upon, but for movement relative to such bottle, a plurality of individual indicators

50 supported upon and separately movable relative to said support, from nonindicating to indicating position, each of said indicators having a generally flattened face engageable with the bottle and held there against by the bottle-supported support, for retention in an indicating position, but being biased to remain, unless moved into such engagement, in nonindicating position, and each 55 indicator having a second flattened face likewise engageable with the bottle to hold the indicator in nonindicating position so long as the support is fully engaged with the bottle.
